Primary Examiner — Justin M Jonaitis*Assistant Examiner* — Samantha K Pollack(57) **CLAIM**

The ornamental design for a phototherapy neck wrap, as shown and described.

DESCRIPTION

FIG. 1 is a perspective view of a phototherapy neck wrap in a folded position showing my new design.

FIG. 2 is a perspective view thereof shown in an unfolded position.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the figures depict stitching and form no part of the claim.
